PITCHER OR SIMILAR ARTICLE

Douglas L. Jocelyn, Detroit, Mich.

Application August 28, 1953, Serial No. 26,619

Term of patent 14 years

(Cl. D44—21)

To all whom it may concern:

Be it known that I, Douglas L. Jocelyn, a citizen of the United States of America, residing at Detroit, in the county of Wayne and State of Michigan, have invented a new, original, and ornamental Design for a Pitcher or Similar Article, of which the following is a specification, reference being had to the accompanying drawing, forming part hereof.

Fig. 1 is a top plan view of a pitcher or similar article, showing my new design;

Fig. 2 is a sectional view taken along line 2—2 of Fig. 1;

Fig. 3 is a rear elevational view of that shown in Fig. 1;

Fig. 4 is a sectional view taken along line 4—4 of Fig. 3;

Fig. 5 is a side elevational view of that shown in Fig. 1; and,

Fig. 6 is a bottom plan view thereof.

The essential features of my design reside in those portions shown in full lines.

I claim:

The ornamental design for a pitcher or similar article, as shown and described.

DOUGLAS L. JOCELYN.
